UNITED STATES PATENT OFFICE.

PAUL A. LUNDBLAD, OF LINDEN, CALIFORNIA.

RAILWAY-CROSSING GUARD.

Application filed February 24, 1925. Serial No. 11,140.

To all whom it may concern:

Be it known that I, PAUL A. LUNDBLAD, a citizen of the United States, residing at Linden, county of San Joaquin, State of California, have invented certain new and useful Improvements in Railway-Crossing Guards; and I do declare the following to be a full, clear, and exact description of the same, reference being had to the accompanying drawings, and to the characters of reference marked thereon, which form a part of this application.

This invention relates to devices to be installed on highways adjacent railway crossings to prevent traffic on the highways from passing onto the railway when a train is approaching.

The principal object of my invention is to provide a guard device preferably operated in conjunction with a suitable warning or stop signal, which when in operative position, will engage the wheels of a vehicle trying to pass the same and will puncture any wheel with a pneumatic tire, and will mutilate any solid rubber tire. This action may seem drastic, but it must be remembered that many automobile drivers are reckless and pay no attention to ordinary warning signals. Some of them never even trouble to slow down at crossings, preferring frequently, with disastrous consequences, to take a chance of beating the train to the crossing.

My device is especially intended to save such drivers from their own carelessness, since once caught by the guards or even knowing of their existence and operation the drivers would thereafter come to a stop before the guards were reached rather than risk certain damage to the tires of their cars.

The guards are only raised to their operative positions so that they will function as above stated when a train approaches and at other times are out of the way so that vehicles may run over the same without interference or damage either to the guards or to themselves.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Figs. 1 and 2 are perspective elevations of my improved guard structure as installed on a highway in the operative position and showing different arrangements of the guards.

Fig. 3 is an enlarged transverse section through a control box as on the line 3-3 of Fig. 1.

Fig. 4 is a similar view taken adjacent a guard tooth as on the line 4-4 of Fig. 1.

In these Figures 3 and 4, the teeth are shown in their lowered or inoperative positions.

Referring now more particularly to the characters of reference on the drawings, the numeral 1 denotes a rigid flat plate of suitable width and extending the full width of the highway 2 flush with the same and located a certain distance ahead of a railway crossing the highway.

The plate is provided with a plurality of slots 3 spaced transversely of the road and extending longitudinally thereof in which slots fit sharp pointed teeth 4. These teeth are non-turnably fixed on a single shaft 5 which is journaled onto and under the plate adjacent the ends of the slots nearest the railway crossing. These teeth are so disposed on the shaft and the latter disposed relative to the plate 1 in such a manner that when the teeth are lowered they will lie flush with the surface of the plate as shown in Fig. 4. The pointed ends of the teeth are then supported on a depressed ledge 1a provided with the plate.

The plate is preferably formed with a shallow trough 6 extending the full length thereof a certain distance under the teeth so as to permit of a certain amount of dirt being taken care of without preventing the proper seating of the teeth within the slots.

Owing to the location of the shaft with respect to the railway crossing, as above stated, when the teeth are raised at a suitable angle as shown in Figs. 1 and 2, they will project toward the wheels of the vehicle on the highway approaching the crossing. The teeth are of sufficient length so that when thus disposed they will not tend to flatten down with the pressure of a wheel thereagainst but instead will tend to pierce the tires, and are sufficiently sharp to do this if the vehicle has sufficient momentum.

At the same time with the approach of a vehicle in the opposite direction or after it has once crossed the railway the guard teeth will be lowered with the weight of the 5 wheels thereon so as not to offer resistance to their passage. The guard teeth are either spaced so as to catch any wheel, as shown in Fig. 1 or so that while one wheel may pass clear the other wheel will be caught, as 10 shown in Fig. 2.

The teeth are normally held lowered as shown in Fig. 4 by suitable counterweight means 7 fixed on the shaft 5 preferably at both ends of the same. These counter- 15 weights are located and enclosed in watertight housings 8 mounted in connection with plate 1 at the ends thereof.

The teeth are preferably raised to an angle of about 45° by suitable means as 20 hereinafter shown, and are prevented from further upward movement by a stop arm 9 fixed on the shaft 5 and adapted to abut against a fixed lug 10 mounted in each housing 8.

25 A suitable form of electric means is employed for raising the teeth, such means being operated by a train on the track approaching the highway, the same character of track circuit being employed as is used 30 in connection with the operation of the ordinary electrically actuated signal means commonly used.

In the present instance I have shown a 35 curved solenoid 11, there being preferably one solenoid in each of the housings 8. The circuit wires 12 from the solenoids extend from the housings to the track circuits. The core 13 for each solenoid is mounted on a radial arm 14 fixed on the shaft 5, the core 40 and solenoid being on a common arc and concentric with the shaft 5.

In operation with the movement of a train onto that section of track which is wired to operate the device the solenoid will 45 be energized, causing the guards to be raised and they will remain raised until the circuit is broken by the passage of the train clear of the wired track section.

If, however, a vehicle on the highway ap- 50 proaches the guards when raised from across

the track the guards will be lowered by the pressure of the wheels of the vehicle thereon temporarily overcoming the action of the solenoid without damage, since the raising influence of the latter on the guard teeth is 55 solely magnetic.

From the foregoing description it will be readily seen that I have produced such a device as substantially fulfills the objects of 60 the invention as set forth herein.

While this specification sets forth in detail the present and preferred construction of the device, still in practice such deviations from such detail may be resorted to as do not form a departure from the spirit of 65 the invention, as defined by the appended claims.

Having thus described my invention what I claim as new and useful and desire to secure by Letters Patent is:

1. A railway crossing guard structure for highways comprising a flat plate member adapted to extend across a highway substantially level therewith, said plate having a plurality of transversely spaced slots extending lengthwise of the highway, a turnable shaft supported from and under the plate at one end of the slots, teeth fixed on the shaft and normally seated in the slots, and means applied to the shaft for turning the 80 same to cause the teeth to assume a predetermined angle relative to the plate. 75

2. A railway crossing guard structure for highways comprising a flat plate member adapted to extend across a highway substantially level therewith, said plate having a plurality of transversely spaced slots extending lengthwise of the highway, a turnable shaft supported from and under the plate at one end of the slots, teeth fixed on the shaft and adapted to seat in the slots, means applied to one end of the shaft for turning the same to cause the teeth to be raised to a predetermined angle, and independent means acting to cause the teeth to be lowered to a seating position in the slots when the raising means ceases to function. 85 90 95

In testimony whereof I affix my signature.

PAUL A. LUNDBLAD.
